United States Patent Office.

JAMES JENKINSON, OF BROOKLYN, NEW YORK, ASSIGNOR TO DANIEL D. WINANT, OF THE SAME PLACE.

Letters Patent No. 71,621, dated December 3, 1867.

IMPROVEMENT IN CHALK-HOLDERS FOR BILLIARD-CUES.

The Schedule referred to in these Letters Patent and making part of the same.

TO ALL WHOM IT MAY CONCERN:

Be it known that I, JAMES JENKINSON, of Brooklyn, in the county of Kings, and State of New York, have invented, made, and applied to use, a certain new and useful Chalk-Holder for Billiard-Cues, &c.; and I do hereby declare the following to be a full, clear, and exact description of the said invention, reference being had to the annexed drawing, making part of this specification, wherein—

Figure 1 is a longitudinal section of said chalk-holder, and

Figure 2 is a cross-section of the same.

Similar marks of reference denote the same parts.

Billiard-players are in the habit of using chalk upon the ends of their cues, to prevent them slipping on the ball and giving an incorrect movement to the same. The chalk is usually held in one hand, and applied to the cue while held in the other hand. This soils the fingers, and is very inconvenient to players.

The nature of my said invention consists in a chalk-holder that can be attached at any convenient part of the table or easily-accessible place, against the chalk in which holder the end of the cue can be pressed, so as to chalk the same; and I provide a spring by which the holder is allowed to yield when pressed upon, and a spirally grooved axis causes a partial rotation as the parts move, so as to rub the chalk on the cue.

In the drawing, *a* represents a portion of the billiard-table or other support for the chalk-holder *b*. *i* is the chalk secured into the holder by a screw-ring, *c*, which ring guides the cue as well as retains the chalk. *d* is a rod forming an axis for the chalk-holder, and extending through the head *e* of the tube *f*. Said rod *d* has one or more spiral grooves in it, in order that a rotary movement may be given to the chalk-holder as it is pressed back, and *g* is a spring to throw the chalk-holder forward again. *h* is an ornamental surrounding to the tube *f*, of any desired character.

What I claim, and desire to secure by Letters Patent, is—

1. A chalk-holder formed substantially as set forth, for chalking billiard-cues and similar articles, when pressed against the chalk in said holder, as specified.
2. The rod *d* and spiral, in combination with the chalk-holder, for the purposes set forth.
3. Forming the chalk-holder *b* with a screw-ring, *c*, to secure the chalk and guide the cue, as set forth.

In witness whereof, I have hereunto set my signature, this twenty-fourth day of August, A. D. 1867.

Witnesses:

GEO. D. WALKER,

GEO. T. PINCKNEY.

J. JENKINSON.
